UNITED STATES PATENT OFFICE.

ANTONIO D. SERINO, OF SOUTH BOSTON, MASSACHUSETTS.

DESIGN FOR A SHOE.

Application filed February 20, 1928. Serial No. 25,497. Term of patent 7 years.

To all whom it may concern:

Be it known that I, ANTONIO D. SERINO, a subject of the Italian Government, residing at South Boston, county of Suffolk, Commonwealth of Massachusetts, have invented a new, original, and ornamental Design for a Shoe, of which the following is a specification, reference being had to the accompanying drawing, forming part thereof.

Fig. 1 is a perspective view, showing my new design.

Fig. 2 is a plan view showing my new design.

I claim:

The ornamental design for a shoe, as shown.

ANTONIO D. SERINO.
